UNITED STATES PATENT OFFICE.

JAMES McKECHNIE, OF BARROW-IN-FURNESS, ENGLAND, ASSIGNOR TO VICKERS
LIMITED, OF LONDON, ENGLAND.

CONSTRUCTION OF INTERNAL-COMBUSTION ENGINES.

1,206,722.

Specification of Letters Patent. Patented Nov. 28, 1916.

Application filed February 12, 1916. Serial No. 77,937.

To all whom it may concern:

Be it known that I, JAMES McKECHNIE, a subject of the King of Great Britain, residing at Naval Construction Works, Barrow-in-Furness, in the county of Lancaster, England, have invented certain new and useful Improvements in the Construction of Internal-Combustion Engines, of which the following is a specification.

10 This invention relates to the construction of internal combustion engines of the balanced kind employing three pistons, the central one of which has an area approximately equal to the combined areas of the 15 outer pistons and moves in an opposite direction to the latter.

My invention provides certain improvements in engines of this kind (especially two-stroke cycle engines) which allow of 20 greater compactness and economy in construction and increased efficiency.

The means for cooling piston rods and pistons in engines of this kind is described and claimed in the application of James 25 McKechnie Ser. No. 106634 filed June 29, 1916, which is a division of the present application.

According to my invention two compression spaces are provided, each comprising 30 the space between the outer end of one of the smaller pistons and the outer end of one of the smaller cylinders, and also a passage between the smaller and larger cylinders. The fuel may be sprayed through two injection 35 valves without the admixture of air or the usual air spraying device may be employed. The spray is directed across the upper end of each side cylinder toward the middle of the engine. To obtain the most efficient com-

40 bustion I may practically confine the compression space of each small cylinder to a transverse channel formed by channeling the piston end and the end wall of the cylinder, the piston at the conclusion of its outer 45 stroke almost meeting the cylinder end except at the channel, which preferably widens from its outer or spraying end to its inner end, where it joins the passage leading to the central cylinder. The central piston may 50 serve also as an air compressor for the supply of scavenging air, for this purpose the central cylinder being provided with an extension above the piston, forming a chamber in which the air is compressed.

55 In an engine of the three piston balanced

type and of large size, it is difficult to provide efficient water cooling for the central piston and piston rod by ordinary methods and I propose to employ an improved water cooling system in which the water is 60 introduced and escapes through pipes or channels extending along the axis of the piston and piston rod and passing through the piston head.

A convenient form of valve gear for operating the two injection valves and also the air starting valve comprises a cam shaft with a double or reversing cam for each injection valve and a double cam for the starting valve, the shaft being displaceable 65 axially for forward or reverse drive. A hand wheel and screw device may be used to move the cam shaft for regulating and reversing. Two fuel pumps are preferably used, one for each injection valve. The 70 pumps may be in the same casing and driven from a pair of eccentrics on a shaft geared to the crank shaft through reducing gear.

In order that the invention may be clearly understood and readily carried into effect, 80 the same will be described more fully with reference to the accompanying drawings, in which:—

Figure 1 is a vertical section of an engine embodying the various features of my invention. Figs. 2 and 3 are elevations of the said engine taken at right angles to each other, with some details in section; Fig. 4 is a section of the upper part of the central cylinder and piston showing a method of 85 fitting a scavenging pump; and Fig. 5 is a 90 vertical section, on an enlarged scale, of the cooling arrangement.

A is the engine casing.

B is the central cylinder and C, C are 95 the outer cylinders.

D is the large central piston and E, E are the smaller side pistons working in the opposite direction to the piston D and with a combined cross sectional area equal to that 100 of the central piston.

F is the crank shaft with central crank f and two side cranks f' connected respectively to the central and side pistons. The central crank is provided with the short 105 thick connecting rod d leading from the tubular piston rod d' belonging to the piston D. Connecting rods e are provided between the side cranks f' and the side trunk pistons E.

G is a fixed inner tube and G' an outer tube leading the cooling water through the central piston rod d' and piston D.

H, H' are a pair of double or reversing cams for the injection valves J and H' is a double cam for the starting valve K, the cams H and H' being fitted on the cam shaft h which is displaceable axially for regulating and reversing by the hand wheel h'.

10 L is the fuel pump casing.

The central cylinder B is in open communication with both of the side cylinders C through the passages c and at the end of the compression stroke, in the position shown in Fig. 1, the large piston D approaches the end of its cylinder so closely as to leave only the minimum clearance permissible. There are therefore two compression spaces, one for each side cylinder, comprising the passages c and a transverse channel e' in the upper end of each of the pistons E; these pistons also approach closely to the cylinder ends, except for the channels e', which lead diametrically across

25 the pistons from the inner passages c to the spraying nozzles or valves situated at J at the outer sides of the cylinders C. The ends of the cylinders C are suitably formed to complete the transverse channels and to

30 confine the compression space at the end of the stroke practically to these channels and the passages c. In large engines of the present type it is of importance to be able to spray the fuel in such a manner that intimate mixture is obtained throughout the compression space and by separating the compression space into two parts each having its own spray and, moreover, by forming each compression space as a channel

35 along which the spray is inwardly directed, the greatest efficiency of spraying and fuel combustion is obtainable. As already mentioned each channel e' may widen from the outer end, where the nozzle J is placed, to

40 the inner end, where it leads into the passage c. The passage c is made large enough to give a free outlet to the exhaust gases and the scavenging air, the air entering through ports e' in the small cylinders and escaping

45 through exhaust ports b' in the large cylinder, on uncovering by the respective pistons C and B. A non-return air valve K' may be placed at the top of one of the outer cylinders C for use in air starting and a

50 safety valve M may be placed at the top of the other cylinder.

The casing A is provided with the water jacket a around the central cylinder B and the side cylinders C, the lower part of the jacket also surrounding the central part a' of the casing, through which the tubular piston rod d' passes, so that the water jacket assists in cooling this rod.

55 As already mentioned, it is desirable to cool the thick central piston rod by a spe-

cial water cooling device comprising the fixed inner and outer tubes G and G' and extensions through the piston and piston rod. Water is introduced by the inlet g through the fixed tube G that leads through the center of the cylinder or pump cover and passes into the end of the piston rod tube g', which slides upon the tube G as the piston reciprocates. The outer fixed tube G' having an outlet g² at its upper end surrounds the central inlet tube G, leaving an annular channel for the outward flow of the water, this outer tube passing through a stuffing box in the upper end of the piston rod d'.

70 The tube g' (which for convenience in fitting is made in three sections) extends from the outer end of the rod d' to just within the piston D, which is hollow. A small collar on the upper end of the tube g' at g³ closes the annular passage at the top of the tube g' immediately above openings g⁴ formed in the piston rod and piston and leading to the interior of the latter, return openings g⁵ passing back from the upper 75 part of the piston chamber to the water channel in the rod d'. The lower section g⁶ of the central tube g' is perforated at g⁶ to allow of communication with the annular return channel formed between the tube and 80 the inner wall of the tubular piston rod.

85 The cooling water flows downwardly through the central tubes G and g' to the lower end of the piston rod d', thence upwardly through the annular passage surrounding the tube g' to the openings g⁴ into the interior of the piston D, back through the return openings g⁵ to the annular passage inside the piston rod and thence to the outlet g² through the annular passage between the two fixed tubes G and G'. An 90 efficient circulation through all parts of the piston and piston rod exposed to high temperature is thus obtained.

95 The valve gear for the starting and injection valves is shown in Figs. 2 and 3. As already mentioned the two double cams H and H' are mounted on the same shaft h, which can be displaced axially for regulating and reversing purposes by the wheel h' and screw h². The timing valve K for air starting, from which a connection passes to the non-return air valve K' on one of the cylinders C, is shown in section in Fig. 2 with the valve stem meeting one element of the air valve cam H'. For starting in the reverse direction the shaft h is shifted to the right to bring the second cam element into operation. The air supply is cut out or in by the cut out valve K² shown in section in Fig. 3 and operated by the starting hand wheel h acting through the worm k' and worm quadrant h². The valves K and K' are operative only when the air supply is turned on by the valve K². A connection 100

7 from the quadrant k^2 to the fuel pump casing L cuts off the fuel supply when the valve K^2 is open, by, for example, holding open the fuel suction valve.

5 The two double cams H for the two fuel injection valves J are shaped to admit of timing and variable fuel supply by axial adjustment of the shaft h in a manner well known. They operate the valves simultaneously through the lever connections j and by moving the shaft h past the central dead position the cams serve for reverse drive.

It is preferred to place two fuel pumps in the pump casing L, each pump supplying its own injection valve J, which may be arranged to inject under high pressure liquid fuel unmixed with air, the fuel entering the cylinder in the form of a spray. The pumps are driven through rods l^2 by the half speed eccentrics l^2 (Fig. 1) geared to the crank shaft F through gearing l^3 the intermediate wheel of which drives the lubricating pump L' through the eccentric l^4 (Figs. 1 and 3).

l^5 is the fuel inlet pipe and l^6 is an outlet pipe leading to an injection valve J.

If the central piston D is to serve also for scavenging purposes, by utilizing its upper end, the construction of the cylinder B and piston D may be modified as shown in Fig. 4, the piston D being extended at D' through the cylinder and provided with a flange d^2 in the enlarged cylinder extension B', so that the flanged end of the piston D forms a pump piston of increased area, sweeping out at each stroke a sufficient volume of air to serve for the scavenging air supply of the three cylinders. The extension or pump cylinder B' is provided with air inlet and outlet valves b' and b^2 and an air chamber b^3 to which the air supply pipe leading to the cylinders C is connected at b^4 . The air inlet or supply pipe is shown at c^2 in Fig. 3, the air passing into the cylinders C through the inlet ports c' (Fig. 1) already referred to. The pump may be double acting, as shown, the under side of the piston flange d^2 being utilized by placing air valves b' and b^2 both at the upper and lower ends of the pump cylinder B'.

50 Fig. 4 does not show the cooling means for the piston rod d' , but the arrangement of tubes shown in Fig. 1 may of course be employed in conjunction with the air compressor of Fig. 4.

55 The general operation of an engine constructed on the lines illustrated is similar to that of an ordinary two stroke engine with ignition on Diesel lines. The method of ignition, however, forms no parts of the present invention. Starting with the engine in the position shown in Fig. 1, the air has already been fully compressed and is now confined to the small spaces left in the side cylinders C by the channels e' on the top of the pistons E and the short com-

municating channels c leading to the central cylinder B. At about the maximum compression the cams H operate the injection valves J and a fine spray of fuel is forced by the fuel pumps through the spraying nozzles into the two compression spaces, the spray being directed inwardly along the channels e' of the pistons E. The compression in the cylinders C is sufficient to ignite the fuel and combustion follows on the usual lines. The pressure acts equally on the pistons D and E, which move in opposite directions but exert torque upon the shaft F in the same direction owing to the oppositely placed cranks f and f' . The power generated in the cylinder B is approximately equal to the combined powers in the cylinders C so that good balance of pressures is obtained. The oppositely moving masses are also chosen to give as perfect a balance as possible and to reduce the vibration to a minimum. When the end of the working stroke is reached the exhaust ports b' in the cylinder B are uncovered by the piston D and at about the same point of the stroke the inlet ports c' in the two side cylinders C are uncovered by the pistons E and scavenging air passes through these ports into both side cylinders and then through the passages c into the central cylinder B and out through the exhaust port. A clear path is thus provided between the inlet at one end of the cylinder spaces and the exhaust at the other end. The pistons and cylinder ends are formed to insure a good sweep for the air, the ends of the side cylinders and the tops of the side pistons sloping slightly up toward the center while the lower end of the central piston D is conical. On the inward stroke of the pistons the ports c' and b' are closed and compression of the charge is effected, completing the usual two-stroke cycle.

What I claim and desire to secure by Letters Patent of the United States is:—

1. In an internal combustion engine, a large central cylinder, two side cylinders having a combined cross section approximately equal to that of the large cylinder and connected to the latter by passages, a large piston in the central cylinder adapted at the end of the compression stroke almost to meet the cylinder end so as to leave no compression space in the said cylinder, two small side pistons acting oppositely to and balancing the pressures on the large piston, two separate compression spaces each made in the form of a transverse channel leading from the outside edge of a small cylinder to one of the said passages leading to the central cylinder, and an injection valve at the outer end of each channel and directed inwardly toward the central cylinder.

2. In an internal combustion engine, a large central cylinder, two side cylinders

- having a combined cross section approximately equal to that of the large cylinder and connected to the latter by passages, a large piston in the central cylinder adapted at the end of the compression stroke almost to meet the cylinder end so as to leave no compression space in the said cylinder, two small side pistons acting oppositely to and balancing the pressures on the large piston, 5 a transverse channel in the end of each of the small pistons, each channel forming a narrow compression space leading from the outer edge of the small cylinder to the passage communicating with the large cylinder, and an injection valve at the outer edge of each small cylinder and directed 10 along the corresponding channel.
3. In an internal combustion engine, a large central cylinder, two side cylinders 15 having a combined cross section approximately equal to that of the large cylinder and connected to the latter by passages, a large piston in the central cylinder adapted at the end of the compression stroke almost to meet the cylinder end so as to leave no compression space in the said cylinder, two small side pistons acting oppositely to and balancing the pressures on the large piston, 20 two separate compression spaces each made 25 in the form of a transverse channel lead-

ing from the outside edge of a small cylinder to one of the said passages leading to the central cylinder, an injection valve at the outer end of each channel and directed inwardly toward the central cylinder, and 35 a separate fuel pump for each valve and pump driving gear connected to the crank shaft.

4. In an internal combustion engine, a large central cylinder provided with exhaust ports in its walls, two side cylinders each provided with air inlet ports in their walls and having a combined cross section approximately equal to that of the large cylinder and connected to the latter by passages, a large piston in the central cylinder adapted at the end of the compression stroke almost to meet the cylinder end so as to leave no compression space in the said cylinder, two small side pistons acting oppositely to and balancing the pressures on the large piston, two separate compression spaces each made in the form of a transverse channel leading from the outside edge of a small cylinder to one of the said 40 passages leading to the central cylinder, and an injection valve at the outer end of each channel and directed inwardly toward the central cylinder. 45

JAMES McKECHNIE.
